DESIGN FOR A LUNCH BASKET OR ANALOGOUS ARTICLE

Vernis K. Shuttleworth, Scarsdale, N. Y., assignor to American Can Company, New York, N. Y., a corporation of New Jersey

Application November 11, 1936, Serial No. 65,860

Term of patent 14 years

To all whom it may concern:

Be it known that I, Vernis K. Shuttleworth, a citizen of the United States residing at 34 Drake Road, Scarsdale, in the county of Westchester and State of New York, have invented a new, original, and ornamental Design for a Lunch Basket or Analogous Article, of which the following is a specification, reference being had to the accompanying drawing, forming a part thereof.

Figure 1 is a perspective view of a lunch basket or analogous article showing my new design, the view illustrating the cover of the basket closed and the handles in carrying position; and

Fig. 2 is a perspective view similar to Fig. 1 and illustrating the cover of the basket in partially raised position and the handles swung back out of the way of the cover.

I claim:

The ornamental design for a lunch basket or analogous article, as shown and described.

VERNIS K. SHUTTLEWORTH.
